NOVELTY HAT

John E. Briese, Monterey Park, Calif.

Filed July 16, 1962, Ser. No. 70,940

Term of patent 14 years

(Cl. D3—13)

FIGURE 1 is a side elevational view of a novelty hat showing my new design;

FIGURE 2 is a front elevational view looking from right to left at FIGURE 1;

FIGURE 3 is a top plan view; and

FIGURE 4 is a vertical section thereof taken substantially on the plane of line 4—4 of FIGURE 2.

The dominant features of the design reside in the portions shown in full lines.

I claim:

The ornamental design for a novelty hat, as shown and described.
